UNITED STATES PATENT OFFICE.

JOHN VASICEK, OF LAGRANGE, TEXAS.

PENCIL.

No. 915,180.

Specification of Letters Patent. Patented March 16, 1909.

Application filed June 15, 1908. Serial No. 438,636.

To all whom it may concern:

Be it known that I, JOHN VASICEK, a citizen of the United States, residing at La-
5 grange, in the county of Fayette and State
of Texas, have invented a new and useful
Pencil, of which the following is a specifica-
tion.

This invention relates to lead pencils and
its object is to provide a simple and durable
device of this character having adjustable
means for holding a lead so that the same
can be conveniently adjusted beyond the end
of the body of the pencil whenever it becomes
worn or broken at the point.

15 Another object is to provide a device of
this character the parts of which can be
readily assembled.

With these and other objects in view the
invention consists of certain novel features
20 of construction and combinations of parts
which will be hereinafter more fully described
and pointed out in the claims.

In the accompanying drawings is shown
the preferred form of the invention.

25 In said drawings: Figure 1 is a central
longitudinal section through a pencil con-
structed in accordance with the present im-
provements, the stem being shown on an en-
30 larged scale with the middle portion re-
moved. Fig. 2 is a section on line A—B,
Fig. 1. Fig. 3 is a longitudinal section
through the butt end of a modified form of
pencil.

Referring to the figures by characters of
35 reference, 1 designates a pencil body, the
same being preferably reduced annularly at
one end as indicated at 2. This body has a
central cylindrical bore 3 at one side of which
is arranged a longitudinal bore 4 commun-
40 icating with the central bore 3 through a slot
5. An angular passage 6 is formed longitudinally
within the body diametrically opposite the bore 4 and opens into the central
bore 3. This passage constitutes a guide
45 way as hereinafter set forth. A conical cap
7 having a flange 8 at one end is arranged at
one end of the body 1 so that said flange 8
will frictionally engage the reduced end 2 of
the body. This cap has a central bore 9 de-
50 signed to register with the central bore 3 and
a socket 10 is formed within the cap and con-
stitutes a bearing for a trunnion 11 formed
at one end of a feed screw 12. This feed
screw extends longitudinally within and
55 throughout the length of the bore 4 and is
designed to rotate therein, there being a

trunnion 13 extending from the screw and
journaled within a reduced opening 14 formed
in the butt end of the pencil. A gear 15 is
secured to the trunnion 13 and meshes with
a gear 16 formed within a cap 17. This cap
has a central stud 18 journaled within the
middle portion of the butt end of the pencil.
The outer face of said cap may be milled or
otherwise finished so that the same can be
conveniently rotated to actuate gear 15 and
screw 12. A holder 19 is mounted to re-
ciprocate within the bore 3 and has a rack
20 extending therefrom and into slot 5, said
rack being in mesh with screw 12. A guide
70 head 21 also extends from the holder 19 and
is mounted to slide within the guide passage
6. Oppositely disposed flexible jaws 22 are
formed at one end of the holder 19 and have
inwardly extending projections 23. These
75 jaws are designed to fit upon opposite faces
of the reduced end of a lead 24 the diameter of
which is such as to permit the same to readily
slide within the central bore 3. The reduced
end of the lead is shaped preferably as indi-
80 cated in Fig. 1 so as to permit jaws 22 and
the extensions 23 to fit snugly thereupon.

When it is desired to feed the lead 24 out-
ward through cap 7 the cap 17 is rotated and
the gears will therefore cause the screw 12 to
revolve and actuate the rack 20. Holder
19 will therefore be slid longitudinally within
bore 3, it being held against rotation by the
rack 20 and also by the guide head 21.
Instead of providing the cap 17 and gears 15
and 16 a milled head 25 may be connected
to the neck 26 of a screw 27 as shown in Fig.
3. With the construction the butt end of
the body 29 is preferably reduced as shown
at 29 so as to permit a guard cap 30 to be slid
over the end of the body and thus conceal
the head 25 when not in use.

It is to be understood that a pencil such as
herein described can be conveniently manu-
factured, it being designed to form the body
100 of hard rubber or similar material which can
be conveniently molded.

What is claimed is:

1. The combination with a body having
parallel communicating bores therein; of a
105 feed screw mounted to rotate in one of the
bores, a rack engaged by the screw and
mounted to slide within the other bore, and
a marker engaging device movable with the
rack and within the last mentioned bore.

2. The combination with a body having
parallel longitudinally communicating bores

therein; of a holder slidable within one of the bores, a rack thereon, and a feed screw mounted to rotate within the other bore and engaging the rack.

5. 3. The combination with a body having parallel longitudinally communicating bores; of a holder mounted to slide within one of the bores, a rack thereon, a feed screw mounted to rotate within the other bore and engaging the rack, and means upon one end of the body for rotating the screw.

10. 4. The combination with a body having parallel communicating longitudinal bores, a cap detachably connected to one end of the body, a holder mounted to slide within one of the bores and into the cap, a rack upon the holder, and a feed screw in the other bore and engaging the rack.

15. 5. The combination with a body having parallel communicating longitudinal bores, and a cap detachably mounted upon one end of the body and having a bore communicat-

ing with one of the longitudinal bores; of a holder mounted to slide within the last mentioned longitudinal bore, a rack upon the 25 holder, and a feed screw within the other longitudinal bore and engaging the rack.

6. The combination with a body having parallel communicating longitudinal bores; of a holder mounted to slide within one of the bores, and a feed screw mounted to rotate in the other bore, means upon the holder for engaging the feed screw, a gear revolvable with the feed screw, and a cap mounted to rotate upon the body and meshing with 30 35 and disposed to actuate the gear.

In testimony that I claim the foregoing as my own, I have hereto affixed my signature in the presence of two witnesses.

JOHN VASICEK.
